(57) CLAIM

The ornamental design for a wheelchair frame, as shown and described.

DESCRIPTION

FIG. 1 is a rear perspective view of a wheelchair frame of the new design;

FIG. 2 is a right side elevational view of the wheelchair frame of FIG. 1;

FIG. 3 is a left side elevational view of the wheelchair frame of FIG. 1;

FIG. 4 is a top plan view of the wheelchair frame of FIG. 1; FIG. 5 is a bottom plan view of the wheelchair frame of FIG. 1;

FIG. 6 is a front elevational view of the wheelchair frame of FIG. 1;

FIG. 7 is a rear elevational view of the wheelchair frame of FIG. 1;

FIG. 8 is a rear perspective view of a second embodiment of a wheelchair frame of the new design;

FIG. 9 is a right side elevational view of the wheelchair frame of FIG. 8;

FIG. 10 is a left side elevational view of the wheelchair frame of FIG. 8;

FIG. 11 is a top plan view of the wheelchair frame of FIG. 8;

FIG. 12 is a bottom plan view of the wheelchair frame of FIG. 8;

FIG. 13 is a front elevational view of the wheelchair frame of FIG. 8; and,

FIG. 14 is a rear elevational view of the wheelchair frame of FIG. 8.

The portions of the Figures shown as lines with a dash-dash pattern indicate unclaimed structure and form no part of the claimed design.

The portions of the Figures shown as lines with a dash-dot pattern are wireframe lines indicating transitions in contour that form no part of the claimed design.

1 Claim, 14 Drawing Sheets
